UNITED STATES PATENT OFFICE

RICHARD D. GALLAGHER, JR., OF NEW YORK, N. Y.

DRAFT-RIGGING FOR RAILWAY-CARS.

1,215,644.

Specification of Letters Patent.

Patented Feb. 13, 1917.

Application filed May 9, 1914, Serial No. 837,550. Renewed August 21, 1916. Serial No. 116,190.

To all whom it may concern:

Be it known that I, RICHARD D. GALLAGHER, Jr., a citizen of the United States, residing at New York, in the county and State of New York, have invented certain new and useful Improvements in Draft-Rigging for Railway-Cars; and I do hereby declare the following to be a full, clear, and exact description of the same, reference being had to the accompanying drawings, forming part of this specification, and to the figures and letters of reference marked thereon.

This invention relates to draft rigging for railway cars, the objects of the invention being to make a very strong structure which will occupy a very limited space and at the same time a structure which provides for the proper flexibility of movement of the cars with relation to each other without seriously cramping or of distorting any of the parts of the rigging, thus adapting the device for use in connection with cars having no platforms and but a little overhang beyond the bolsters, such, for example, as ore cars and the like, although it will be understood that the invention may be embodied in draft rigging for any type of cars wherein it is desired that a rigging of minimum dimensions shall be employed.

The invention consists in certain novel details of construction and combinations and arrangements of parts all as will be now described and pointed out particularly in the appended claims.

Referring to the accompanying drawings,

Figure 1 is a plan view of a draft rigging embodying the present improvements;

Fig. 2 is a section in a horizontal plane substantially central of the device but with certain of the parts in plan;

Fig. 3 is a section in a central vertical plane longitudinally of the device, with the yielding pressure resisting member in dotted lines;

Fig. 4 is an end view with the coupler shank in section;

Fig. 5 is a transverse section substantially on the line 5—5 of Fig. 3;

Fig. 6 is a similar section substantially on the line 6—6 of Fig. 3;

Fig. 7 is a section substantially on the line 7—7 of Fig. 3;

Fig. 8 is a section substantially on the line 8—8 of Fig. 3;

Fig. 9 is a side elevation of the coupler shank; and

Fig. 10 is a perspective view of the preferred type of yielding pressure resisting mechanism, a plain cylindrical barrel being shown and a portion of the barrel and box for the friction members being broken away.

Like letters of reference in the several figures indicate the same parts.

In the drawings, the longitudinal center sills A which are conveniently of channel iron with the webs arranged vertically as usual, are adapted for the reception between them of the draft rigging of the present invention, which is rigidly attached to and incorporated with said center sills. It will be understood that the sills A referred to may be either the sills which extend through the car from end to end, or supplemental sills attached to the through-sills in any usual or preferred manner. The framing of the car, which is connected with the sills A, may be of any preferred character, the parts illustrated being the diagonal members B, B' and B'', a transverse sill C and portions of the bolster at C'.

Between the extremities of the sills A there is rigidly mounted a casting indicated generally by the letter D, said casting being of a proper formation to receive and support the shank of the coupler and to constitute the abutment for the front follower of the draft rigging. It thus performs the functions of a carry iron for the coupler, of an abutment for resisting draft strains transmitting through the coupler shank to the yielding pressure resisting members in rear of the casting, and it may also form the ultimate stop for the coupler head when driven inwardly by buffing pressure.

In the preferred construction, the face of the casting is formed with a flange portion d which overlies or extends beyond the end of the sills and having at its center a substantially rectangular opening extending rearwardly through the casting for the reception of the rectangular coupler shank E. The lateral dimension of the opening through the casting is considerably greater than the corresponding dimension of the coupler shank as will presently appear, and while the bottom of the opening is substan-

tially horizontal and adapted to support the bottom surface of the coupler shank through an intermediate wear-plate d' , the upper wall of the opening is preferably flared upwardly to a very slight degree, as shown at d^2 in Fig. 3, whereby the shank will be supported rigidly in a horizontal line so as to prevent any dropping or sagging of the coupler, and at the same time, the coupler is permitted a certain amount of vertical and horizontal clearance to allow of the necessary or desirable flexibility between the cars united by the couplers.

The shank E of the coupler is provided with an elongated transverse opening e, Fig. 9, for the reception of a transverse pin F. This pin extends through openings in the side walls of the casting D and through the webs of the sills A, and is preferably of oval-cross section with its greatest transverse dimension in the line of draft strains or so as to oppose the withdrawal of the coupler shank from the casting.

To permit of longitudinal flexibility of the coupler the openings d^3 in the casting D through which the pin F projects are elongated to permit the forward movement of the pin in unison with the forward movement of the coupler, and the opening e in the coupler shank is elongated to permit of the movement of the coupler and its shank inwardly independently of the said pin and the parts connected therewith. On outward movement from normal position, therefore, the pin and coupler shank move in unison, but on inward movement from normal position, the pin remains stationary and the coupler shank alone moves inwardly.

The normal position of the coupler longitudinally is maintained by the yielding pressure resisting member of the rigging, and this member is located intermediate a front follower plate G which occupies a position within a rearwardly projecting flange d^4 of the casting D and a rear follower casting H which abuts against a fixed stop or abutment I. The stop or abutment I is in the form of a heavy casting rigidly mounted between the sills A and preferably forming a part of the center framing of the car. It is provided with a vertical opening i therein to facilitate the insertion and removal of the center pin which works through the bottom plate I' of the bolster. The rear follower or block H is provided with a transverse opening for the reception of a pin K preferably of a cross section substantially corresponding to that of the pin F and the two pins are connected together by side links L, which at their forward ends project into the opening in the front casting D on each side of the coupler shank, as will be readily understood from Figs. 4 and 5. To secure flexibility a very slight clearance is provided in the openings of the links

through which the pins project, and for convenience in assembling and maintaining the parts in their proper assembled position, the front pin F is provided with a head f at one end and at the opposite end with a washer 70 and cotter pin f', but the rear pin K is held in place and the links in proper engagement therewith by the webs of the sills A, as will be readily understood from Fig. 2. To permit of the assembling, the said webs are provided at a point intermediate the two abutments with an opening or openings a of proper size to admit the pin K, and when the rear follower block H and links have been initially positioned with their openings 80 in line with the opening a, the pin is inserted and all of said members pushed back to their normal position.

Between the follower plate G and follower block H is the yielding pressure resisting member, which is preferably of the well known Sessions standard friction draft gear type, having wedge blocks O mounted in a friction box P on each side of a center wedge P'. The center wedge P' is held up with yielding pressure by the springs P² and the friction box is supported by a barrel or extension P³. The springs P² and barrel P³ rest against the follower plate G while the wedge blocks O rest against the front face of the rear follower block H, whereby pressure in a rearward direction against the follower plate G tends to push the barrel and friction box rearwardly, and to compress the springs P² directly from the forward end and indirectly through the wedge blocks at the rear end. Forward movement of the coupler is transmitted through the side links to the rear follower block H and through it to the wedge blocks 105 O and P' and to the spring which is thereby compressed, movement in either direction creating a vast amount of friction with little recoil in the well understood way. The whole arrangement of parts shown in Fig. 110 10 has been herein designated the yielding pressure resisting member, and while the particular type illustrated is preferred, inasmuch as it has certain advantages to be presently pointed out in this particular combination, it is obvious that other types of yielding pressure resisting members may be employed, without material change in the other features of the invention.

At the rear end, the yielding pressure resisting member and follower blocks are held in proper position and in alignment by a supporting strap Q best seen in Fig. 8. At an intermediate point they are supported by a bottom plate Q' which is shaped to rest 125 on the strap Q at the rear end and be detachably connected with the casting D at the front end by bolts q, best seen in Fig. 4. This arrangement permits the parts to be readily assembled from the under side of the 130

car, or to be removed for repair by the detachment of the plate Q'. The parts are held against upward movement by arch-like straps R and R' bridged over the same from the webs of the sills A, as best seen in Fig. 8 of the drawings.

The castings D and I which substantially fill the space between the sills A are made sufficiently heavy to withstand the strains to 10 which they are subjected, being for this purpose provided with strengthening ribs extending both laterally and longitudinally of the sills and with flange-like faces resting against the sills for the passage of attaching rivets extending through the flanges of the castings and webs of the sills.

With the type of pressure resisting member hereinbefore particularly referred to, it is found that the wedge blocks will readily 20 adjust themselves to any slight lateral or upward play of the parts without decreasing the efficiency, thus with the wedges O arranged vertically with relation to each other, as shown in dotted lines in Fig. 3, and in 25 plan in Figs. 1 and 2, lateral strains on the coupler which tend to advance one of the side links L farther than the other and to correspondingly tip the follower block H will simply result in the wedges O assuming 30 an intermediate angle with relation to the wedge P' and the friction faces of the parts will remain in contact practically throughout their whole areas, whereby the efficiency is maintained even under adverse 35 circumstances. The rear end of the coupler shank takes a firm bearing against the forward follower plate G and any slight lateral movement of the coupler will have its center of movement at the contacting surfaces 40 forming the bearing between the coupler shank and front follower, if the parts be acting under buffing pressure. If under the draft strain, the shank is drawn away from the front follower plate and the center of 45 movement will be in the connection with the pin and links as aforesaid.

Under draft strains it will be understood that the coupler, the side links and rear follower blocks all move forwardly in unison, 50 and ultimate strains may be transmitted to the casting D through the engagement of the pin F with the front ends of the slots or openings in said casting. Under buffing strains the pin F, side links and follower block H all remain stationary, the coupler shank with the front follower plate G and 55 parts of the yielding pressure resisting member alone moving rearwardly, the ultimate strain being taken up by the casting D, if heavy enough to cause the seating of the coupler head against the same.

Having thus described my invention, what I claim as new and desire to secure by Letters Patent is,—

1. In a draft rigging for railway cars, the

combination with spaced longitudinal car sills, of a casting bridging the space between and rigidly connecting the ends of said car sills, said casting embodying a face plate bridging the ends of the sills and having a 70 central substantially rectangular opening therethrough for the reception of a correspondingly shaped coupler shank, whereby the coupler will be supported and guided by the casting, a rear follower block, a stop for 75 limiting the rearward movement of said block, a transverse pin loosely mounted in said casting and forming one member of a connection between the coupler shank and the rear follower block, said pin being movable with the coupler shank under draft strains and stationary under buffing strains, side links connecting said rear follower block and pin, and having their forward ends extended into the rectangular opening 80 in the casting whereby the lateral movement of the coupler shank relatively to the casting is limited by the forward ends of the side links, a front follower plate seated against the rear face of the casting and 85 bridging the coupler shank opening therein and against which the coupler shank rests, and a yielding pressure resisting member interposed between the front follower plate and rear follower block. 90

2. In a draft rigging for railway cars, the combination with the spaced longitudinal car sills, a casting bridging and rigidly connecting the ends of said sills, said casting having a face plate forming a stop for the 100 head of the coupler and having a central substantially rectangular aperture therethrough for the coupler shank, a seat on its rear face for a forward follower plate, and a guiding flange projecting rearwardly of 105 said seat, the follower plate normally resting in said seat within the flange and bridging the rear end of the opening through the casting, a rear follower block, a casting rigidly connecting the sills in rear of said 110 follower block and forming a stop therefor, pins extending transversely through the follower block and casting at the end of the sills, side links connecting said pins, a yielding pressure resisting member mounted between the follower plate and follower block 115 for yieldingly resisting relative movements of said parts toward each other, and a coupler shank having an elongated aperture therein through which the pin at the forward end of the side link passes, whereby the coupler shank may move rearwardly 120 independently of said pin to compress the pressure resisting member through the action of the forward follower plate. 125

3. In a draft rigging for railway cars, the combination with the spaced longitudinal car sills, of a casting rigidly mounted between and bridging the ends of said sills, said casting embodying a face plate form- 130

- ing an ultimate stop for the inward movement of the coupler head and having a substantially rectangular opening therethrough in which the coupler shank is guided and mounted, a transverse longitudinally elongated opening for a coupler shank engaging pin, a seat on the rear face of said casting for the reception of the follower plate, and a guiding flange projecting rearwardly around said seat, a rear follower block, a stop for limiting the rearward movement of the block, a follower plate seating against the front casting, a yielding pressure resisting member intermediate the follower plate and follower block, side links connected at their rear ends with the follower block, a transverse pin mounted in the opening in the front casting and coöperating with said side links, and a coupler shank loosely mounted on said pin and normally resting at its rear end against the follower plate, said coupler shank having a longitudinally elongated opening for the reception of the pin, whereby under draft strains the follower block, links, pin and coupler will move forwardly in unison, and under buffing strains the coupler and forward follower plate will move rearwardly independently of the link and pin.
4. In a draft rigging for railway cars, the combination with the spaced longitudinal car sills, a casting rigidly connecting and bridging the space between said sills at their ends, said casting having an opening therethrough for the support and guiding of a coupler shank, a front follower plate resting against said casting, a rear follower block, a stop casting against which said rear follower block rests, side links with connections at the forward ends thereof for co-operation with the coupler shank, a transverse pin extending through the rear follower block and links, the ends of said pin being confined between and guided by the webs of the sills, said webs having an opening therein for the insertion of said pin located forwardly of the normal position of the pin to facilitate the assembling of the parts.
5. In a draft rigging for railway cars, the combination with the spaced longitudinal car sills, yielding pressure resisting member, rear follower block, stop for limiting the rearward movement of said block, and front follower plate, of a casting rigidly connecting and bridged between the front ends of the sills, said casting embodying a front plate forming an ultimate stop for the coupler head under buffing strains and having a substantially rectangular opening therethrough for the reception of the coupler shank, a seat at its rear side for the follower plate, a guiding flange projecting rearwardly from said seat, and a transverse pin opening therein elongated longitudinally of the car, a transverse pin mounted in said pin opening for retaining the coupler shank in position, and side links connecting said pin and rear follower block, substantially as described.
6. In a draft rigging for railway cars, the combination with spaced longitudinal car sills, a casting bridged between and rigidly connecting the ends of said sills and embodying a face plate overlying the ends of said sills, said casting having a longitudinal coupler shank opening therein, a transverse follower plate seat at the rear end of said opening, and a transverse longitudinally elongated pin opening in the casting intersecting the coupler shank opening, a follower plate seated against the rear of the casting, a rear follower block having a rearward extension with a transverse pin opening therein, a casting rigidly mounted between the sills and constituting a stop against which said follower block rests, transverse pins mounted in the openings in the follower block and front casting respectively, side links connecting said pins, and a yielding pressure resisting member interposed between the follower block and follower plate for yieldingly opposing the relative movement of said members toward each other.
7. In a draft rigging for railway cars, the combination with the spaced longitudinal car sills, a casting rigidly connecting and bridged between the ends of said sills, said casting having a longitudinal coupler shank opening therein with a transverse follower plate seat at its rear end, and a coupler shank pin opening intersecting the coupler shank opening and elongated longitudinally thereof, side links having their forward ends located within the coupler shank opening and connected with said pin, a rear follower block having a transverse pin opening therein, a pin located in said opening and engaging the rear ends of the side links, a stop casting for limiting the rearward movement of the follower block, a yielding pressure resisting member mounted between the follower block and follower plate and a supporting strap for the yielding pressure resisting member comprising a rear member having its ends connected with the longitudinal car sills, and a front member overlapping the rear member and detachably secured to the casting.
8. In a draft rigging for railway cars, the combination with spaced longitudinal car sills, of a casting bridged between and rigidly connecting the ends of said sills and embodying a face plate overlying the ends of said sills, said casting having a longitudinal coupler shank opening therein, a transverse follower plate seated at the rear end of said opening, and a transverse longitudinally elongated pin opening in the casting.

casting intersecting the coupler shank opening, a follower plate seated against the rear of the casting, a rear follower block having a rearward extension with a transverse pin opening therein, a casting rigidly mounted between the sills and constituting a stop against which said follower block rests, transverse pins mounted in the openings in the follower block and front casting respectively, side links connecting said pins and having their forward ends extended into the coupler shank opening in the front casting whereby the lateral movement of the coupler shank relatively to the casting is limited by the forward ends of the side links, and a yielding pressure resisting member interposed between the follower block and follower plate for yieldingly opposing the relative movement of said members toward each other.

9. In a draft rigging for railway cars, the combination with spaced longitudinal car sills, of a casting bridged between and rigidly connecting the ends of said sills, said casting having a longitudinal coupler shank opening therein, a transverse longitudinally elongated pin opening in the casting intersecting the coupler shank opening, a follower plate seated against the rear of the casting, a rear follower block having a transverse pin opening therein, transverse pins mounted in the openings in the follower block and casting respectively, side links connecting said pins and having their forward ends extended into the coupler shank opening in the front casting whereby

the lateral movement of the coupler shank relatively to the casting is limited by the forward ends of the side links, and a yielding pressure resisting member interposed between the follower block and follower plate for yieldingly opposing the relative movement of said members toward each other.

10. In a draft rigging for railway cars, 45
the combination with spaced longitudinal
car sills, of a casting bridged between and
rigidly connecting the ends of said sills, said
casting having a longitudinal coupler shank
opening therein, a transverse longitudinally 50
elongated pin opening in the casting intersecting
the coupler shank opening, a follower plate seated
against the rear of the casting, a rear follower block having a
transverse pin opening therein, transverse 55
pins mounted in the openings in the follower
block and casting respectively, side
links connecting said pins and having their
forward ends thickened and extended into
the coupler shank opening in the front 60
casting whereby the lateral movement of the
coupler shank relatively to the casting is
limited by the forward ends of the side
links, and a yielding pressure resisting member 65
interposed between the follower block
and follower plate for yieldingly opposing
the relative movement of said members to-
ward each other. 70
